UNITED STATES PATENT OFFICE

HARRY DENTON PIPER, OF CHICAGO, ILLINOIS, ASSIGNOR TO WESTERN ELECTRIC COMPANY, INCORPORATED, OF NEW YORK, N. Y., A CORPORATION OF NEW YORK

APPARATUS FOR HEAT-TREATING METALS

Application filed November 14, 1922, Serial No. 600,864. Renewed July 28, 1927.

This invention relates to apparatus for heat treating metals.

An object of the invention is to provide such an apparatus in which the heating and cooling of the metal may be continuously performed and the temperatures of the heating and cooling regulated within close limits.

Another object of the invention resides in an improved means for conducting heat away from the metal subsequent to its subjection to the heating means.

The apparatus herein disclosed is particularly adapted for heat treating a copper wire to be used as an electrical conductor for the transmission of intelligence, the conductor being wrapped with a metallic alloy tape having certain electrical characteristics which are controlled to some extent by the character of the heat treatment administered thereto. A full disclosure of the metallurgical constituency of the tape or of its electrical characteristics or of the specific heat treatment are not necessary to a complete understanding of the present invention which is not limited to this use but may be employed for other purposes and the invention is only to be limited by the spirit and scope of the appended claims.

Other objects, features, and advantages of the invention will be set forth in detail in the following description and particularly pointed out in the claims.

In the accompanying drawings which illustrate one embodiment of the invention,

Fig. 1 is a side elevation partly broken away, illustrating an apparatus made in accordance with the invention;

Fig. 2 is an enlarged vertical sectional view of the left hand end of the cooling tube;

Fig. 3 is an enlarged fragmentary vertical sectional view of the cooling tube;

Fig. 4 is a vertical sectional view taken on the line 4—4 of Fig. 3; and

Fig. 5 is an enlarged fragmentary side ele-

vation showing the exit end of the tube through which the strand is fed.

Although the apparatus disclosed in the drawing is particularly designed for heat treating metal in strand form, it is to be understood that the apparatus may be modified to treat metal in other forms, without departing from the spirit and scope of the invention.

Referring now to the drawings in detail in which like reference numerals designate similar parts throughout the several views:

Numerals 10 and 11 indicate two furnaces which are in juxtaposition. These furnaces may be of any suitable type and heated in any desired manner. They are illustrated as being electric furnaces heated by coils diagrammatically illustrated at 12 and 13 respectively. The furnace 10 is longer than the furnace 11 and is maintained at a higher temperature, the purpose of which will be hereinafter explained. Instead of two furnaces, it is to be understood that a single furnace having two zones maintained at different temperatures may be utilized, or the heating means otherwise modified, without departing from the spirit and scope of the invention.

Suitably supported within the furnaces 10 and 11 is a metallic tube 14 which communicates with a cooling tube 15, as shown in Fig. 2.

The strand to be heat treated is fed from a supply reel 16 over a suitable curved guide 17 and pushed through the tubes 14 and 15 by means of a caterpillar feeding mechanism 18. As the strand passes from the discharge end of the cooling tube 15, it is acted upon by a second caterpillar feeding mechanism 19, which serves to take up slack in the strand, the heat treated strand being taken up on a storage reel 20. For a detailed illustration and description of the construction and operation of the caterpillar mechanisms 18 and 19, reference is made to the Patent No. 1,653,215, issued to Frederick S. Kochendorf.

fer and A. E. Schulz, on December 20, 1927. For the sake of simplicity the drawings only illustrate one heating tube and one cooling tube, but it is to be understood that in practice a plurality of tubes similar to the tube 14 may be mounted within the furnaces 10 and 11 and that a plurality of cooling tubes 15 may be utilized therewith. The caterpillar feeding mechanisms are designed to receive five strands so that this number of heating and cooling tubes may be utilized without necessitating any modification in the feeding mechanism.

In the heat treatment of the metallic alloy tape heretofore referred to, it has been found desirable to relatively gradually heat the tape to a predetermined temperature, maintain the tape at or above this temperature for a certain time interval and then reduce the temperature of the tape to a predetermined degree within a certain period of time. Since the apparatus disclosed is particularly designed for performing this heat treatment, the furnace 10 is heated to a degree slightly higher than the temperature at which it is desired to maintain the tape for the predetermined length of time, the tape leaving the furnace 10 and entering the furnace 11 which is kept at the temperature at which it is desired to maintain the tape for a certain length of time. By heating the furnace 10 to a degree slightly above that at which it is desired to maintain the tape, it is possible to keep the tape at an even predetermined temperature. The furnace 10 is made considerably longer than the furnace 11 in order that the tape may be raised to the required temperature during its passage through the furnace, the length of the furnace 10 determining the speed at which the conductor having the tape wrapping may be drawn therethrough. Since the tape is at approximately the desired temperature when it enters the furnace 11, this furnace may be of a length just sufficient to maintain the tape at the desired heat for the desired length of time.

For a full disclosure of the composition of the alloy tape, its application to the conductor and the subsequent heat treatment, reference is made to the patents to Gustaf W. Elmen, No. 1,586,884, issued June 1, 1926; Oliver E. Buckley, No. 1,586,874 issued June 1, 1926; and Gustaf W. Elmen, No. 1,586,887, issued June 1, 1926.

The heating tube 14 and cooling tube 15 are connected by a short length of tubing 21 (Fig. 2). The heating tube 14 and connecting tube 21 are the same diameter and are externally screw threaded within collars 22 and 23 respectively, so as to abut each other, the said collars being connected together by bolts 24. The connecting tube 21 is of smaller diameter than the cooling tube 15 and is externally screw threaded to mesh with internal screw threads in the cooling tube. Threaded

upon the outside of the cooling tube 15 and the connecting tube 21 is a plug 25 having an external screw threaded flange 26 upon which a pipe 27 concentric with the cooling tube 15 is threaded. The thickness of the flange 26 spaces the pipe 27 and cooling tube 15 apart so as to form a tubular chamber 28 between them. The other end of the chamber 28 is closed by a suitable plug 29 (Fig. 1), having an opening through which the end of the cooling tube 15 projects. A suitable cooling fluid such as water or oil is constantly circulated through the chamber 28 entering by a pipe 30 and being discharged through a pipe 31, the said fluid being circulated by a pump or other suitable means (not shown). In order to insure a thorough circulation of the cooling fluid around the cooling tube, a coil spring 32 is fitted within the chamber 28 surrounding the cooling tube, the spring forming a tortuous passage through which the cooling fluid is forced from the entrance pipe 30 to the exit pipe 31.

The conductor 1, in being pushed and pulled through the heating tube 14 and cooling tube 15 lies on the bottom thereof, as shown in Fig. 2. In order to promote radiation of the heat from the conductor to the inner peripheral surface of the cooling tube 15, a plurality of heat conducting bars 33 constructed of copper or other suitable metal of high heat conductivity are placed within the cooling tube in end to end relation, as shown in Fig. 3. The members 33 fit relatively loosely within the cooling tube and are provided with a triangular groove 34 (Fig. 4), embracing the conductor 1. In order to keep the grooves 34 in alignment, the members 33 are prevented from turning, one relative to the other, by means of dowel pins 35. The conductor passes through the cooling tube 15 in the direction indicated by the arrow (Fig. 3) and the frictional contact between the members 33 and the conductor tends to pull the said members out of the cooling tube. A spring clip 36 fastened adjacent the exit end of the cooling tube engages the end of the outermost heat conducting member 33, holding all of the said heat conducting members within the cooling tube. However, in the event that the friction between the conductor and the heat conducting members becomes too great, the said members will be drawn out of the cooling tube against the action of the spring retaining member 36. Due to this construction, friction between the heat conducting members and the conductor, which might tend to place undue tension on the conductor is prevented. In depositing the heat conducting members 33 within the cooling tube 15 they are inserted into the latter through the exit end thereof, one after the other, the insertion of each member push-

ing the one in advance of it farther into the cooling tube, as is readily understood.

By providing the heat conducting members 33, a rapid radiation of heat from the conductor is accomplished, and by mounting them in the manner above described, all undue friction between them and the cooling tube is prevented. Should the cooling tube be made to relatively closely fit the conductor, although rapid radiation of the heat from the conductor might be accomplished, should the tapered conductor vary in diameter so as to press against the inner periphery of the cooling tube, the entire conductor might be subjected to undue tension.

In the heat treatment of the metal alloy tape heretofore mentioned, it has been found desirable to subject the conductor and the tape wrapping to as little tension as possible during the heat treatment, and for this reason the construction of cooling tube, above described, is provided. This construction, however, may be found desirable in the heat treatment of other metals, and the invention is not to be limited to its use in connection with the metallic tape above referred to, but only in so far as is defined in the appended claims.

In order to provide both a non-oxidizing and a non-reducing atmosphere in the heating tube 14, nitrogen under pressure is forced into the said tube through a pipe 37, screw threaded in the collar 22, which is provided with a passage 40 formed at an angle so as to direct the gas into the heating tube 14, and in a direction opposite to that in which the material being treated is moving. The nitrogen entering through the pipe 37 is forced into the heating tube 14, and provides both a non-oxidizing and non-reducing atmosphere, and in its passage through the tube sweeps out any other gases that may be present therein.

What is claimed is:

1. An apparatus for processing material subsequent to heat treatment comprising inner and outer receptacles, the inner receptacle supporting and physically engaging the material for substantially the entire length of the receptacle, a heat conducting metallic member within the inner receptacle also engaging the material, and a cooling fluid in the outer receptacle for conducting the heat from said inner receptacle and said metallic element as received from said material.

2. In a treating apparatus for metals in strand form; a cooling chamber, means for feeding the strand through said chamber, said cooling chamber comprising a receptacle to receive the strand, a heat conducting member loose within said receptacle and engaging the strand, and means of such character retaining the heat conducting member within said receptacle that predetermined frictional contact between the strand and the member

will draw the latter out of the receptacle as the strand is fed therethrough.

3. In a treating apparatus for metals in strand form, a cooling chamber, inner and outer receptacles, a cooling fluid within the outer receptacle, the inner receptacle adapted to receive the strand, means for feeding the strand through the chamber, a metallic heat conducting member loose within said inner receptacle and engaging the strand, and means of such character retaining the heat conducting member within said receptacle that predetermined frictional contact between the strand and the member will draw the latter out of the receptacle as the strand is fed therethrough.

4. In a treating apparatus for metals, a cooling chamber, means for feeding metal to be treated through said chamber, said cooling chamber comprising an inner and an outer receptacle, the inner receptacle adapted to receive and support the metal, a heat conducting member within the inner receptacle and engaging the metal supported by the receptacle, a cooling medium in the outer receptacle for conducting the heat from said inner receptacle received from said metal.

5. In a treating apparatus for metals, a cooling chamber comprising an inner receptacle to receive the metal, an outer receptacle, a heat conducting member in said receptacle contacting with said metal, a cooling medium in the outer receptacle, and means for causing said cooling medium to flow in a tortuous path through said outer receptacle to conduct away the heat received from said metal.

6. In a treating apparatus for metals, a cooling chamber comprising a receptacle to receive the metal, and a heat conducting member mounted loosely within said receptacle to permit its movement in accordance with variations in the dimensions of the metal being treated and provided with an inverted V-shaped groove along which said metal is advanced.

7. In a treating apparatus for metals, a cooling chamber comprising a receptacle supporting the treated metal and in direct contact therewith, a heat conducting member smaller than the interior cross-sectional dimension of the receptacle to permit its movement transversely of the receptacle upon the occurrence of any variation in the dimension of the metal being treated and provided with a groove along which the metal is advanced and the walls thereof engage for conducting heat from said metal.

8. In a treating apparatus for metals subsequent to heat treatment comprising a receptacle supporting the treated metal, a heat conducting member contained in said receptacle and engaging the metal for the purpose of conducting heat therefrom, an outer receptacle, and a helical member positioned in said outer receptacle for causing a cooling medium

to flow in a tortuous path from said outer receptacle.

9. In a treating apparatus for metals, a cooling chamber comprising an inner receptacle to receive the metal, a plurality of lengths of a conducting element in abutting relation and pinned to each other engaging said metal, an outer receptacle, and means in the outer receptacle for causing a cooling medium to flow in a tortuous path for conducting the heat from said inner receptacle and the conducting element.

10. In witness whereof, I hereunto subscribe my name this 4th day of Nov. A. D., 1922.
